UNITED STATES PATENT OFFICE.

JOHN P. DOHERTY, OF EAST ST. LOUIS, ILLINOIS.

WRENCH.

SPECIFICATION forming part of Letters Patent No. 612,712, dated October 18, 1898.

Application filed January 31, 1898. Serial No. 668,630. (No model.)

To all whom it may concern:

Be it known that I, JOHN P. DOHERTY, of the city of East St. Louis, St. Clair county, State of Illinois, have invented certain new and useful Improvements in Wrenches, of which the following is a full, clear, and exact description, reference being had to the accompanying drawings, forming a part thereof.

My invention relates to ratchet-wrenches; and it consists of the novel construction, combination, and arrangement of parts herein-after shown, described, and claimed.

Figure 1 is a front elevation of my improved ratchet-wrench. Fig. 2 is a sectional view taken approximately on the line 2 2 of Fig. 1. Fig. 3 is a vertical sectional view taken approximately on the line 3 3 of Fig. 2 and showing a modified construction of the nut-engaging head of my improved ratchet-wrench. Fig. 4 is a view in perspective of an adjustable plate made use of in carrying out my invention.

Referring by numerals to the accompanying drawings, 1 indicates the wrench-handle, which is of any suitable size and length, there being a ring or collar 2 formed integral with the lower end of said handle. Passing through this ring 2, in opposite sides thereof, are the screws 3, the purpose of which will be presently shown.

4 indicates a rectangular head, with the rear end of which is formed integral a circular projection 5, that is provided in its periphery with a continuous groove 6, and said projection 5 is of such a size as that it will easily rotate within the ring 2. When this projection is properly located in said ring 2, the screws 3 are properly seated in said ring 2, and by so doing their points will engage in the groove 6, and thereby rotatably retain the head 4 within the ring 2.

Formed through the head 4 and projection 5 is a rectangular opening 7, and arranged to fit in a recess 8, formed in the bottom of the head 4, is a plate 9, which may, if desired, have its upper face corrugated or roughened in any suitable manner. This plate 9 is provided with a pair of guide-pins 10, which pass through suitably-arranged apertures in the lower portion of the head 4, and passing upwardly through an aperture formed in the lower portion of this head is a set-screw 11,

having a winged head 12. The point of this set-screw 11 engages in a suitably-formed recess in the under side of the plate 9, and by 55 means of said set-screw said plate is elevated. By this construction the wrench may be arranged to engage nuts of different size.

Formed in the head 4 at the point where the projection 5 joins said head is a continuous row of ratchet-teeth 13. Located upon the front face of the handle 1 immediately above the head 4 is a clip 14, which is so formed as that its lower end lies at a point a slight distance in front of the handle 1, and 60 between said lower end and the handle 1 is pivoted a pair of pawls 15, that extend in opposite directions. The rear ends of said pawls are provided with flat faces 16 at right angles to each other, and the lower free ends 70 of the inverted-U-shaped springs 17 bear immediately upon these flat faces. This spring 17 is located beneath the clip 14 and held in position by a lug 18, extending rearwardly from said clip 14. Only one of the pawls 15 75 is made use of at a time—that is, when one is thrown into engagement with the ratchet-teeth 13 the opposite one is elevated, as shown in Fig. 3. When either of the pawls is elevated, it is held in position by the pressure 80 of the arm of the spring that bears against one of the flat faces of the elevated pawl.

In Fig. 3 the head 4 is shown with a hexagonal opening instead of a rectangular opening, and when the head is so formed it is 85 adapted for use upon nuts of a uniform size. Therefore in this form of the wrench different heads with different-sized openings must be provided.

By forming the openings 7 all the way 90 through the head the wrench may be located upon an extra long nut or may be located upon a nut through which the bolt projects some distance.

In the preferred form of the wrench said 95 wrench may be used upon nuts ranging in size downwardly from the size of the aperture 7, the only adjustment required being the manipulation of the set-screw 11.

My improved wrench is adapted for a variety of purposes, it being compact, can be used in close quarters and in any position, and it may be instantly adjusted so as to be swung from right to left, or vice versa.

I claim—

1. A ratchet-wrench, constructed with a handle, a cylindrical head integral with one end of said handle, the head 4 rotatably arranged in said first-mentioned head and provided in its periphery with a series of ratchet-teeth, pawls carried by the handle for engaging in said ratchet-teeth, and an adjustable plate carried in said last-mentioned head, substantially as specified.

2. A ratchet-wrench, constructed with a handle, a cylindrical head 2 formed integral with one end of said handle, the head 4 having an angular aperture throughout its length, which head is provided at one end with a peripheral groove, screws passing through the

first-mentioned head and engaging in said groove, spring-actuated pawls carried by the handle and engaging in a series of ratchet-teeth formed in the rotatable head, there being recesses formed in one face of the aperture through the rotatable head, a plate normally located within said recesses and means whereby said plate may be elevated from said recesses, substantially as specified. 25

In testimony whereof I affix my signature in presence of two witnesses.

JOHN P. DOHERTY.

Witnesses:

A. J. McCUALEY,
M. P. SMITH.
